UNITED STATES PATENT OFFICE.

ALBERT CEDERLUND, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR IN LOOM TRANSFERRER.

Application filed November 10, 1927. Serial No. 232,432.

This invention relates to a side slip weft detector of the type mounted in regularly moving transerrer arms and it is the general object of the invention to give a weft detector of this type a straight line motion at the time of weft exhaustion indication which shall be substantially parallel to the surface being detected.

In Patent No. 1,372,316 to Ryon there is shown a weft detector mounted on a regularly moving transerrer and in several other patents detectors of this type are shown, all of them employing a pivoted yarn engaging detector. The transerrer arm itself moves about a pivot which is relatively close to the surface being detected and there results an objectionable arcuate movement on the part of the detector as the transerrer moves downwardly around its supporting stud. The detector, therefore, when in detecting contact with the yarn is being acted on to move in two different arcs, one of them around the pivot of the transerrer arm and the other about the detector pivot. There results a rolling contact between the bobbin and detector, the point of contact moving rearwardly with respect to the detecting surface. The other angular motion is in a plane parallel to the bobbin being detected and because of it the teeth nearer the butt of the bobbin are lifted away from the detected surface and the teeth near the tip of the bobbin are brought into contact with the surface so that there is a constantly changing relation between the detector teeth and the yarn.

It is an important object of my present invention to mount the detector on the transerrer so that the same will move in a substantially straight line which is parallel to the axis of the bobbin being detected, the detector sharing the pivotal movement of the transerrer arm but having no pivotal movement of its own relatively to the transerrer arm.

With these and other objects in view which will appear as the description proceeds, my invention resides in the combination and arrangement of parts hereinafter described and set forth in the claims.

In the accompanying drawings wherein one form of my invention is shown,

Fig. 1 is a vertical central section through that part of the transerrer arm extending over the shuttle and showing the detector in

contact with a full supply of yarn with the indicating plunger in non-indicating position.

Fig. 2 is a view similar to Fig. 1 but with the detector sliding along a substantially exhausted supply of weft and with the plunger in indicating position,

Fig. 3 is a detailed top plan view taken in the direction of arrow 3, Fig. 1,

Fig. 4 is a detailed vertical section on line 4-4 of Fig. 1,

Fig. 5 is a fragmentary horizontal section on line 5-5 of Fig. 1,

Fig. 6 is a vertical section on line 6-6 of Fig. 1, and

Fig. 7 is a diagrammatic view of the transerrer arm and its pivot.

The transerrer arm 10 has a portion 11 extending over and substantially parallel to the bobbin B and has opposite spaced walls 12 between which is located a vertically extending slot 13 in which the operating mechanism of the detector is located. An indicating plunger 14 slidable in the end of the transerrer arm and also in a web 15 is provided with a notch 16 which receives the hooked end of a latch 17. Said latch is pivoted on a pin 18 secured in the walls 12 and has a depending finger 19 to cooperate with the detector carrier to be described. A torsion spring 20 having the upper end extending over one of the walls 12 as shown in Fig. 3 and extending around a portion of the stud 18 and having the other end extend over the horizontal part of the latch as at 21 serves to hold said latch normally in the position shown in Fig. 1, but permits upward yielding thereof under influence either of the detector carrier or the head 22 of the plunger 14. A compression spring 23 is located between a clip 24 secured to the transerrer arm and a shoulder 25 on the plunger and tends normally to move the latter towards the right from the position shown in Fig. 1. An indicating lever L is positioned for cooperation with the plunger and when the latter is in the position shown in Fig. 2 it will engage the lever to rock the same as the transerrer arm moves upwardly after an indicating movement.

The matter thus far described is common construction in this type of detecting mechanism.

My invention relates more particularly to the detector and the means for moving the

same relatively to the bobbin being detected and in carrying my invention into effect I provide a sliding detector carrier 30 formed substantially as shown in Figs. 1 and 6 with 5 the lower end thereof having a horizontal flat portion 31 which extends into the guide slots 32, there being one slot formed on each of the walls 12 and the slots being opposite each other so as to receive the flat portion 10 31. A light tension spring 33 interposed between a portion of the transferrer arm and sliding carrier 30 holds the latter yieldingly against a stop pin 34 fast on the transferrer arm.

15 The means for imparting motion to the carrier slide includes a rod 40 to the right end of which as shown in Fig. 1 is slidably mounted in bore 41 in the transferrer arm and the left end of which is provided with a pair of 20 spaced pins 42 between which the shorter vertical portion 43 of the carrier extends. The left end of the rod extends through said portion 43 and by reason of the pins causes the carrier slide and rod 40 to move together 25 in a horizontal direction. An actuating lever 44 is pivoted as at 45 to the transferrer arm and is normally held in the dotted line position shown in Fig. 1 against a stop pin 46 by means of a compression spring 47 on rod 30 40 located between a pin 48 on the rod and a washer 49 which engages the forked end 50 of the lever 44. A substantially horizontal arm 51 is positioned for engagement with a yielding trip 52 of the type shown in patent 35 to Ryon No. 1,551,219.

The detector element D as shown herein includes a square shank 60 having a pin 61 in the upper end thereof to limit downward movement, said detector extending through 40 the upper horizontal portion 62 of the sliding carrier and also extending through the lower horizontal portion 31. A light compression spring 63 surrounds the shank 60 and is located between the portion 62 and shoulder 64 formed on the detector element D as shown in Fig. 6. The effect of said spring 63 is to hold the detector in down position but to permit the same to yield upwardly.

In operation the transferrer arm is swung 50 downwardly around stud S, Fig. 7, on every detecting beat of the loom, as is set forth the aforesaid patent to Ryon, the detector being held yieldingly in its normal position by the spring 63 and the spring 47 being expanded to hold the lever 44 against the stop 46. The spring 33 holds the carrier 30 to the left against the stop 34 and against the action of spring 47. Said spring 33 is so placed as to exert its force substantially in 55 line with the guides for the lower portion 31 of the carrier. As the transferrer arm descends the horizontal arm 51 will engage the yielding trip 52 which in this instance is normally stationary but may yield under high 60 pressure and the lever 44 will be acted on to

move from the dotted to the full line position shown in Fig. 1. In doing so the spring 47 is compressed and a longitudinal pressure is exerted on the rod 40 tending to move the latter to the right from the position shown in Fig. 1. This tendency, however, does not arise until after the detecting surface 65 has been brought into contact with the surface to be detected, but as soon as it does arise there is a force acting against spring 33 tending to move the parts to the right of the position shown in Fig. 1.

So long as sufficient yarn is present, however, the detector will be held against movement longitudinally of the bobbin, but when 80 the yarn is substantially exhausted so that the bobbin presents insufficient holding contact with the detector the spring 47 acting on pin 48 will move the rod 40 to the right to the position shown in Fig. 2, moving with it the carrier 85 30 and detector D. As the carrier moves to the right the horizontal portion 31 thereof will engage the finger 19 of the latch and rock the same around its pivot to the releasing position shown in Fig. 2, whereupon the compression spring 23 will move the indicating plunger to indicating position as shown in Fig. 2. As the transferrer is raised said plunger will cooperate with the lever L to 90 initiate a change in the loom. At a later time in the upward movement of the transferrer arm the plunger is reset as shown in the Ryon Patent No. 1,551,219.

From the foregoing it will be seen that I have provided a detector which is mounted to move in a direction substantially parallel to the surface being detected and is also placed on a transferrer arm of a weft replenishing loom so that although said arm turns around a relatively short radius yet 100 the change between the detector surface and the surface being detected is reduced to a minimum and is not possessed of the disadvantage inherent in detectors mounted on transferrer arms where the detector has an 105 angular movement with respect to the trans- 110 ferrer arm.

Having thus described my invention it will be seen that changes and modifications may be made therein by those skilled in the art without departing from the spirit and scope of the invention and I do not wish to be limited to the details herein disclosed, but what I claim is:

1. In weft detecting mechanism for a 120 loom having a regularly movable transferrer arm, an indicating plunger slidably mounted on the arm, a latch to hold the plunger in non-indicating position and yielding means to move the plunger to indicating position 125 when the latch is moved to releasing position, a weft detector, and means to guide said weft detector on the transferrer arm to move in a direction substantially parallel to the surface being detected at the time of indica- 130

tion of weft exhaustion, said means maintaining the detector in substantially the same angular position relatively to the surface being detected as the detector moves along the surface being detected, said means moving into engagement with the latch when the detector moves to indicate exhaustion of weft.

2. In weft detecting mechanism for a loom having a regularly movable transferrer arm, an indicating plunger slidably mounted on the arm, a latch to hold the plunger in non-indicating position and yielding means to move the plunger to indicating position when the latch is moved to releasing position, a weft detector member, and a carrier member for the detector member slidably mounted on the transferrer arm and movable in a direction substantially parallel to the length of the surface being detected, one of said members moving into engagement with the latch on an indicating beat of the loom.

3. In weft detecting mechanism for a loom having a regularly movable transferrer arm, an indicating plunger slidably mounted on the arm, a latch to hold the plunger in non-indicating position and yielding means to move the plunger to indicating position when the latch is moved to releasing position, a weft detector, a carrier for the detector slidably mounted on the transferrer arm to move in a direction substantially parallel to the length of the surface being detected, and yielding means interposed between the detector and the carrier and tending to hold the detector normally in low position relatively to the carrier and yielding when the detector engages a sufficient supply of weft and is moved upwardly relatively to the carrier.

4. In weft detecting mechanism for a loom having a regularly movable transferrer arm, an indicating plunger slidably mounted on the arm, a latch to hold the plunger in non-indicating position and yielding means to move the plunger to indicating position when the latch is moved to releasing position, a detector carrier slidably on the transferrer arm into engagement with the latch to release the same and in a direction substantially parallel to the length of the surface

being detected, and a weft detector mounted on the carrier, said detector preventing movement of the carrier when sufficient weft is present and said carrier being movable into engagement with the latch when insufficient weft is present.

5. In weft detecting mechanism for a loom having a regularly movable transferrer arm, an indicating plunger slidably mounted on the arm a latch to hold the plunger in non-indicating position and yielding means to move the plunger to indicating position when the latch is moved to releasing position, a detector carrier slidably mounted on the transferrer arm in a direction substantially parallel to the length of the surface being detected, yielding means tending to move the carrier slidingly with respect to the transferrer arm into engagement with the latch on each detecting beat of the loom, and a weft detector mounted on the carrier to prevent sliding movement of the carrier when sufficient weft is present, said carrier sliding into engagement with the latch when insufficient weft is present.

6. In weft detecting mechanism for a loom having a regularly movable transferrer arm, an indicating plunger slidably mounted on the arm, a latch to hold the plunger in non-indicating position and yielding means to move the plunger to indicating position when the latch is moved to releasing position, a detector carrier member slidably mounted on the transferrer arm in the direction of the length of the surface being detected, a rod connected to the carrier member and guided for sliding movement parallel to the movement of said member, yielding means to exert a force on the rod each detecting beat of the loom tending to move said rod and carrier member in a direction toward the latch, and a weft detector member mounted on the carrier member to prevent movement of the latter toward the latch when sufficient weft is present, said yielding means moving one of the members into engagement with the latch to release the latter when insufficient weft is present.

In testimony whereof I have hereunto affixed my signature.

ALBERT CEDERLUND.
